Application February 1, 1940, Serial No. 316,803

18 Claims. (CL 110—101)

One of the objects of our invention is the provision of a mechanically operated and automatically controlled solid fuel burning appliance and the method of operating the same which so correlates the delivery of fuel to the fuel bed of the furnace, the removal of ashes from said fuel bed and the control of the air supplied to the furnace and of the draft therefrom that will, when burning any selected suitable kind and size of fuel, maintain, during periods when heat is demanded, a substantially uniform predetermined rate of combustion, and will also maintain during periods when heat is not demanded (hereinafter referred to as "idling") a substantially uniform reduced rate of consumption, merely sufficient to maintain the temperature in the combustion portion of the fuel bed above the ignition temperature of the fuel used.

A further object of our invention lies in providing, in a furnace of the foregoing character, a system of automatic controls which will maintain substantially constant combustion conditions in the combustion portion of the fuel bed at the selected rate of combustion thus tending to produce substantial uniformity in the composition of the mixture of gases leaving the furnace.

A further object of our invention is to eliminate the possibility of the formation in the fuel bed, by the fusing together of ash particles set free from the fuel during its combustion, of clinkers too large to readily pass through the openings in, or at the periphery of, the grate.

A still further object of our invention is the limitation to a negligible minimum of the quantity of fly ash particles carried from the fuel bed to the gas passages of the appliance and their deposit therein, during, and for a period after, agitation of the fuel bed for the removal of ashes therefrom.

It is believed that our invention will best be understood by first giving the following general outline of our invention before proceeding with a more detailed description.

The system of automatic control of the operation of a furnace embodying our invention includes devices which are so arranged as to control and relatively time the operation of various elements or combinations of elements, the functions of which, namely, are: draft control, which determines the rate at which fuel is burned and heat generated thereby; control of the stoking operation, which includes the conveying of fuel from the fuel storage bin to the fuel magazine of the furnace; the separation of the ash refuse set free by the combustion of fuel in the fuel bed.

from the unburned fuel therein; and the conveying of such ash refuse from the ash pit of the furnace to a suitable receptacle remote from said furnace.

5 The intermittent type of automatic draft control is preferably employed in a furnace or combined furnace and boiler embodying our invention. Such type of control provides draft sufficient to burn fuel at the maximum selected rate when heat or steam pressure is demanded and barely sufficient draft to maintain the desired temperature of the fuel bed when idling. Natural draft varies with the outside temperature, and may be notably affected by the direction and 10 velocity of the wind. To substantially avoid such uncontrolled variation in draft we employ a motor driven induced draft fan or exhauster to withdraw flue gas from the furnace and deliver it to the chimney, said fan being operated at 15 substantially constant speed so as to produce a substantially uniform pressure differential when running. This fan operates only when heat is demanded, its operation being controlled by the draft control motor which also controls the position of the main air inlet valve which is opened 20 when heat is demanded and closed when the furnace is idling. An idling air inlet valve is also provided which is large enough to admit sufficient air to maintain the desired temperature of 25 the fuel bed during idling periods when combustion is maintained by natural draft. This idling air inlet valve is closed only during the stoking cycle as will be explained later.

To maintain a substantially uniform rate of 30 combustion of a selected kind and size of fuel with a substantially uniform draft, that is, with a uniform pressure differential between the spaces immediately above the fuel bed and immediately below the grate, the depth of fuel in each part 35 of the burning portion of the fuel bed should be kept substantially constant and the total cross sectional area of the voids between the pieces of fuel, through which air and other gases pass, should also be kept substantially constant. To 40 meet these conditions, ashes set free by combustion of the fuel must be removed from the fuel bed at such frequent intervals that ashes are never permitted to accumulate on the grate below the burning fuel in such quantity as to appreciably reduce the depth of burning fuel, and 45 that ashes are never permitted to accumulate in the voids between the pieces of fuel in such quantities as to materially increase the resistance to the flow of air and other gases through 50 the fuel bed. In accordance with our invention 55

the total depth of the burning portion of the fuel bed from its top surface to the supporting grate in each part of said burning portion of the fuel bed is kept substantially constant; the elevation of the upper surface thereof is fixed by the elevation of the lower edge of the fuel magazine and the natural angle of repose of the fuel as it feeds downwardly and outwardly from the magazine by gravity; and the elevation of the bottom of said burning portion of the fuel bed is fixed by the upper surface of the grate, and the frequency of the removal of ashes from the fuel bed is so related to the rate of combustion that the relatively constant conditions in the burning portions of the fuel bed as above described are maintained.

The relatively constant condition of the burning portion of the fuel bed maintained by such method makes possible an exceptionally uniform composition of the flue gases escaping from the furnace with practically no unburned combustible and only a small percentage of free oxygen. Furthermore the frequent removal of free ashes from the fuel bed so limits the quantity of ash particles coming in contact with each other in any place in the fuel bed that when fused together the clinker so formed is so small as to readily pass through the openings in, or at the periphery of, the grate.

The methods employed and a means provided by our invention for securing the correlation, sequence and relative timing of the various operations in the stoking cycle so as to obtain the results described above will be more clearly understood by reference to the attached drawings in which—

Fig. 1 is a diagrammatic view illustrating the controls embodying our invention;

Fig. 2 is a diagrammatic view illustrating a succeeding position of the shaft and associated parts and electrical connections of the draft control motor;

Fig. 3 is a view similar to Fig. 2 illustrating a further succeeding position of the shaft of the draft control motor and the parts and electrical connections associated therewith;

Fig. 4 is a diagrammatic view illustrating a solid fuel furnace and a solid fuel magazine leading to the combustion portion of the fuel bed, an associated follower rod normally resting on the surface of the fuel bed and illustrating the relation of the same to the control system for the furnace;

Fig. 5 is a front view of a cam, secured to the shaft of a pilot motor, which controls the position of the idling air inlet valve and the fuel inlet valve for the furnace;

Fig. 6 illustrates diagrammatically a second cam device, secured to the shaft of a pilot motor, for controlling the operation of the stoker motor;

Fig. 7 is a front view, somewhat diagrammatic in character, illustrating a conveyor for delivering solid fuel to the furnace and an ash conveyor which removes ash from the furnace and carries it to a desired point of discharge, both the fuel conveyor and the ash conveyor being actuated by a common motor;

Fig. 8 is a transverse section through the fuel conveyor; and

Fig. 9 is a side view of a fragmentary section of an endless chain which may be used for conveying fuel.

Like reference characters indicate like parts throughout the drawings.

Any suitable device which utilizes a deviation from the selected standard temperature or pressure to be maintained, may be used to control the operation of the draft control motor, the connections therewith being so arranged that ordinarily, that is, except as hereinafter explained, any drop below the selected temperature or pressure will cause the draft control motor to place the draft producing elements in a draft on position and keep them in such position until the demand for more heat or pressure has been satisfied and will then cause the draft control motor to place the draft producing elements in an idling position until temperature or pressure drops below the selected standard.

To illustrate and describe our invention any one of the usual types of three points, thermostat actuated, switch 10 and the electrical connections therefrom to the draft control motor 11 may be used. The draft control motor 11 so controls the supply of air for combustion to the furnace that the variation of temperature or pressure at the point of control is kept within desired limits. While we have illustrated the three-point switch 10 as a thermostat it will, of course, be understood that a pressure-operated device, or an equastat may likewise be used. The draft control motor 11 causes a shaft 32, to which it is suitably connected, to rotate at a predetermined rate, preferably between 1 and 4 revolutions per minute. Secured to the shaft 32 is a cam 13, the periphery of which is generally circular in form, preferably through an arc of approximately 330° and is concentric with the center of the shaft 32, the remaining portion of its periphery being occupied by an inwardly extending and preferably curved notch 14.

Two conducting spring arms 15 and 16, equipped with suitable contact elements near their lower ends, (Fig. 1) are mounted on suitable conducting supports 17 and 18, respectively, and are disposed at opposite sides of the cam 13, the conducting supports 17 and 18 being provided with suitable laterally extending bosses 19 and 20, respectively, preferably generally triangular in shape, and said bosses being continuously held against the periphery of the cam 13.

In the embodiment of our invention illustrated, current for the operation of the various electric devices embodying our invention is derived from line conductors 251 and 252 connected through a suitable transformer 253 to conductors 25 and 25a. A fixed contact member 21 is connected through a conductor 23 and conductor 201 to the conductor 25 with the parts in the positions illustrated in Fig. 1, and with the boss 19 resting in the notch 14 of the cam 13, the contact 21 is spaced from the contact element of the conducting spring arm 15. Similarly, a fixed contact member 22 is connected through a conductor 24 to a conductor 30 leading from the fixed contact member 29 of the thermostat 10 to one side of the motor 11, the opposite side of which is connected by a conductor 204 to the conductor 25a.

In the position illustrated in Fig. 1, the boss 20 mounted on the arm 16 rests against the circular portion of the cam 13 and is forced outwardly against the contact 22. The arms 15 and 16 are connected to a jumper connection 26 which is connected to a conductor 27 connected to the arm 28 of the thermostat which cooperates with the fixed contacts 29 and 29a.

In accordance with our invention, the draft control motor 11 controls the position of the main inlet valve 34 and the operation or stoppage

of the draft fan motor 44, ordinarily establishing and maintaining a draft on condition when a substandard temperature causes the thermostat arm 28 to make contact with fixed contact 29a, and conversely establishing and maintaining an idling condition when a temperature above standard causes the thermostat arm 28 to make contact with fixed contact 29. The operation of the draft control motor 11 is also interlocked with the operation of the pilot motor 45 which in turn controls the starting and stopping of the stoker motor 88; the methods of this interlocking and purposes thereof are fully described later.

A crank arm 31 (Fig. 4) provided with a crank pin 311 is secured to a shaft 32, actuated by the draft control motor 11, preferably through a speed reducing mechanism, and pin 311 is connected by a flexible element, such as a cable 33, to the main air inlet valve 34 shown pivotally mounted above a draft opening 35 (Fig. 4), the cable passing over suitable idlers 36 and 37 so that when the draft control motor is in the position illustrated in Fig. 4 and indicating a demand for heat, the main air inlet valve is open. A crank arm 38, which may be secured to the end of the shaft 32 opposite to that to which the crank arm 31 is secured, controls switches which, in turn, control the operation of the draft fan motor 44 and prevent the operation of the pilot motor 45 except when the draft fan motor 44 is shut off and the main air inlet valve 34 is closed. A crank pin 381 mounted on the end of the crank arm 38 is connected by a chain 39 or other flexible connection to the upper end of an inclined arm 40 pivoted at 41, on which are mounted two mercury switches 42 and 43 provided with respective contacts. The contacts in the switch 42 are closed when the arm is in its raised position and corresponding to a position where the main air inlet valve is open thereby closing the circuit to the fan motor 44 when the main air inlet valve is open. At the same time, the contacts of the mercury switch 43 are open. The circuit to the fan motor 44 is thus closed through the switch 42 so long as the demand for heat continues and provided another control device, hereinafter described, does not operate to cause motor 11 to open switch 42. The starting circuit for the pilot motor 45 includes contacts disposed at the raised end of the mercury switch 43 so that such circuit is open when the parts occupy the positions indicated in Fig. 1 thereby precluding the possibility of operating the stoker motor when the main air inlet valve 34 is open and the draft fan motor 44 is running.

In accordance with our invention means are provided for conveying a substantially uniform predetermined quantity of fuel from the storage bin to the fuel magazine of the furnace whenever the top surface of the fuel therein subsides below the selected elevation. In the embodiment of our invention illustrated, a follower rod 46 (Fig. 4) passes through an opening 47 in the top cover 48 of the fuel magazine, the lower end of the follower rod normally resting on the top surface of the fuel 49 in the magazine 50. The upper end of the follower rod is connected by a cable 51 to a crank pin 52 on a crank arm 53 mounted on a shaft 54 actuated by the pilot motor 45, the cable 51 passing over suitable idlers 55 and 56. As combustion of the fuel in the furnace proceeds, the surface of the fuel 49 subsides and the follower rod 46, being free to move vertically, descends, sufficient slack being provided in the horizontal portion of the cable to permit the follower rod to

descend independently of its connection to the arm 53 when said crank arm 53 is in the position shown in Fig. 4. The upper end of an inclined bar 58, pivotally mounted as at 59 on a bracket 59a secured to the fuel magazine 50, is so arranged as to assume the position illustrated when the end thereof, which is located in the path of movement of a cross bar 57 mounted above follower rod 46, is not depressed thereby.

When the follower rod descends the inclined bar 58 is tilted counter-clockwise as viewed in Fig. 4 thereby opening the circuit between a first pair of contacts indicated at 61R in a switch 61, mounted on said bar, which contacts are included in circuit with the conductors 202 and 203 in the starting circuit of the draft control motor 11. This movement of bar 58 also causes a circuit to be closed between a second pair of contacts indicated at 61L in switch 61, which contacts are respectively connected to conductors 205 and 206 which in turn are connected to the conductors 30 and 27, respectively. A closure of the circuit through said second pair of contacts 61L and conductors 205 and 206 serves to effect an actuation of the draft control motor 11 to place the arm 38, operated thereby, in the position in which the switch 42 will be open, or, in other words, the motor 11 will be actuated to place the draft control elements in the "idling" position, and will then hold them in that position as long as said closure of the circuit is maintained through the contacts 61L of switch 61.

We have illustrated in Fig. 7 a preferred device for stoking the furnace which comprises means for delivering fuel to the furnace and means for shaking the ashes from the fuel bed and removing the same from the furnace room, which stoking device is controlled by the follower rod, above described, which operates in response to subsidence of fuel in the fuel-magazine or fuel bed of the furnace.

The furnace is provided with a hopper 82 the mouth 83 of which may be inclined as illustrated, the hopper communicating with the magazine 50. The fuel conveyor, indicated generally at 84, passes over a driving sheave 85 on a shaft 86, both the fuel conveyor 84 and the ash conveyor indicated generally at 87 being driven by a common motor 88 through suitable reduction gearing 89. The fuel conveyor preferably comprises spaced blades or vanes 90 (Fig. 8) suitably secured by supporting brackets 91 to an endless chain 92 which passes over an idling sheave 93 located adjacent the mouth of the hopper 82 and is so arranged that the fuel conveyed thereby is delivered to the hopper as the conveyor element approaches the idler 93. In the form of our invention shown, the upper flight of the fuel conveyor is substantially horizontal, the other two flights thereof extending downwardly beneath the fuel chute 741 leading from the fuel storage bin as illustrated in Fig. 7.

The ash conveyor 87 is preferably in the form of a straight link chain 95 which passes over a driving sheave (not illustrated) on the shaft 86 and over a sheave 96 mounted near the bottom and outside of the furnace as illustrated in Fig. 7. The upper flight 951 of the chain 95 passes through the bottom of the ash pit of the furnace and thence upwardly through an inclined tube 97 from the upper end of which ash is delivered to a chute 970 leading to a suitable receptacle (not illustrated). The lower flight 952 of the chain passes downwardly from the sheave 70 on the shaft 86 and beneath the floor 98 of the

ash pit of the furnace. The details of the ash conveyor are more fully illustrated in application Ser. No. 275,612 which was filed by Warren S. Blauvelt in the Patent Office on or about May 25, 1939, and issued June 3, 1942, as Patent No. 2,244,442.

In a preferred arrangement of the furnace, the shaft upon which the sheave 96 is secured has also secured thereto a crank arm 962 which is arranged to rotate and reciprocate the grate 963, upon which the fuel bed rests, through the medium of links 964 and 965 and bell crank 966. Hence, while the stoking device is operated, supplying fuel to the magazine, the grate is moved, thereby agitating the fuel bed and permitting the ashes which have been separated from the burning fuel to fall from the grate to the ash pit, and the ash conveying element of the stoking device removes said ashes therefrom to the ash receptacle.

Further, in accordance with our invention, the follower rod 46 and associated devices which are operated thereby not only control the draft control motor 11 but also control the pilot motor 45 which, in turn, controls the circuit to the stoker motor.

In the illustrated embodiment of our invention, the inclined arm 58 carries switch 61, above described, and a second switch 60. When the follower rod, with the projection 57 thereof engaging the free end of the pivoted bar 58, descends a predetermined distance, the inclination of the two mercury switches 60 and 61 is reversed from that illustrated and, therefore, the mercury in both switches 60 and 61 will flow to the opposite ends thereof. Switch 60 has electrical contacts in one end only and is connected in circuit with mercury switch 43 and the pilot motor 45. The switch 60 is closed only when the follower rod 46 is in its lowered position, indicating a need for additional fuel in the magazine, and, when the movable end of the pivoted arm 40 is in its lowered position, switch 43 also is closed and when both of these switches are closed a circuit to pilot motor 45 is established.

In effect, therefore, the pilot motor 45 is primarily controlled by the follower rod 46 and can start only when the follower rod is down, indicating a need for a charge of fuel. Of course, when the rod 46 drops sufficiently to close switch 60, switch 61 will be actuated to close the circuit through the contacts 61L and through conductors 205 and 206 thereby effecting an actuation of motor 11 to "idling" position or, in other words, motor 11 is actuated to raise crank arm 31 thereby closing the air inlet valve 34, and depressing crank arm 38 thereby opening the circuit through switch 42 to draft fan motor 44 and closing the circuit through switch 43 to pilot motor 45.

With the foregoing arrangement, it will be seen that if the fan motor is in operation when the follower rod 46 drops and closes the switch 60, the pilot motor 45 cannot operate to close the switch to the stoker motor because switch 43 is open. However, when switch 60 is closed, the contacts 61L of switch 61 also close the circuit through conductors 205 and 206 and thereby effect an operation of motor 11 to stop the fan motor, and motor 11, in this operation, also closes the switch 43 and the pilot motor 45 can then operate to place the stoker motor in operation. Switch 42, controlling the fan motor and switch 43 may be so arranged that switch 42 opens substantially when switch 43 closes.

In the foregoing, we have described the circuit to the pilot motor 45 which includes the switches 60 and 43, a closing operation of switch 60 being controlled by the follower rod 46 and switch 43 being actuated to closed or open position by the crank arm 38 which is operated by the draft control motor 11. This circuit serves initially to connect motor 45 across the line when the fuel in the fuel magazine has subsided to a predetermined elevation. In addition we provide a second circuit for the pilot motor 45 which functions to continue the operation of motor 45 after such operation has been started by the closure of the circuit through switches 60 and 43, if said circuit should subsequently be opened, until the shaft 54 driven by said motor 45 shall have been caused to rotate approximately one complete revolution. This second or shunt circuit comprises a conductor 209 which is connected between the line conductor 25 and the resilient conducting arm 210 of a switch indicated generally at 208. Arm 210 is provided with a contact adapted to engage a contact mounted on a second but relatively fixed conducting arm 211 of switch 208. Arm 210 is also provided with a boss 212 which is held in engagement with the periphery of a cam 213 mounted upon and rotatable with shaft 54 which is rotated by pilot motor 45, preferably through a suitable speed reducing mechanism. Cam 213 is provided with a recess 214 in which boss 212 lies when cam 213 is in the position shown, which is its position during periods when motor 45 is not operating. With this arrangement, an energization of motor 45 through the closure of switches 43 and 60 will produce rotation of cam 213 thereby forcing boss 212 out of the recess 214 in the cam surface and maintaining the contacts on the arms 210 and 211 in engagement with each other during substantially a 360 degree movement of rotation of shaft 54. The engagement of the contacts on arms 210 and 211 closes a circuit from line conductor 25 through conductor 209, arms 210 and 211 and a conductor 215 which is connected from arm 211 to one side of motor 45, the other side of the motor being connected directly to the other line conductor 25a. Hence, the second or shunt circuit will maintain an operation of motor 45, after it has been initially energized, to effect approximately one complete revolution of the cam 213 and shaft 54.

The shaft 54 which is actuated by the pilot motor 45 has mounted thereon a crank arm 53 provided with the crank pin 52, as hereinbefore described. To this crank pin is connected the cable 51 which, at the other end thereof, is connected to the follower rod 46. A second cable 511 is connected to crank pin 52 and to a lever 217 which is pivotally supported at one end thereof as indicated at 218. Upon lever 217 is mounted a switch 200 which is so arranged that when the crank arm 53 lies in its raised position the switch is closed and, when the crank arm is lowered, the inclination of switch 200 will be reversed and the switch will be opened. The contacts of switch 200 are respectively connected to conductor 203 and through conductor 219 to one of the first pair of contacts 61R of switch 61, above described. Briefly, switch 200 is included in the circuit with contacts 61R of switch 61 and conductors 202 and 203 to prevent an operation of motor 11 in the event, first, the thermostat 10 closes the circuit when a predetermined drop in temperature to which it is responsive has occurred and, in the further event,

that the follower rod 46 is held in a raised position by its supporting cable 51. In other words, when pilot motor 45 is operated it closes the circuit to the stoker motor, as hereinafter described, and also opens the circuit through switch 200 thereby preventing any operation of the fan motor while the stoker motor is in operation.

Upon the shaft 54 driven by pilot motor 45, are also mounted two cam elements 62 and 75. Cam 62 is designed to effect an opening and closing of the fuel gate 68 in the chute 82 leading to the fuel magazine and cam 75 is designed to control the circuit to the stoker motor 88. An arm 63 controlled by cam 62 is connected by cable 65 passing over pulleys 66 and 67 to the fuel gate 68.

The arm 63, pivoted at one end as indicated at 64 in Fig. 5 so that it can move radially in a vertical plane, is provided with a suitable weight 631 which suffices to keep the outer end of the arm 63, which may be provided with a roller 632, riding upon and supported by the surface of the cam 62. Except as explained below, cam 62 is stationary as shown in Fig. 5 supporting the pivoted arm 63 in its elevated position, in which position thereof the fuel gate 68 closes the opening through which fuel is supplied to the magazine. However, when motor 45 starts and in its operation causes shaft 54 to revolve in a counter clockwise direction, cam 62 will permit arm 63 to be lowered under the force exerted by the weight 631 and fuel gate 68 will thereby be raised.

In the embodiment of our invention herein illustrated, the furnace is provided with a second air inlet opening 74 which is designed to be closed during the period when fuel is supplied to the magazine but which is otherwise open. A closure element 73 for the opening 74 is connected by means of a cable 70 to the cable 65, cable 70 passing over pulleys 71 and 72 and the cables being fastened together as illustrated at some point intermediate pulley 67 and fuel gate 68. Hence, when arm 63 is elevated by cam 62 the closure element 73 is elevated to permit air to enter through the opening 74 but, when arm 63 is lowered, element 73 is also lowered and effects a closure of the air inlet opening 74.

The cam 75, which is also mounted on shaft 54, is preferably formed of two similar cam elements. These elements comprise generally circular surface portions 751 and 752, the surface 751 having a larger radius than the surface 752 and these surfaces being connected by intermediate, sloping surfaces 753. Both of said cam elements may be adjustably fastened on shaft 54 or one of said elements may be fixed thereto. However, by affording relative circumferential adjustment of the cam elements, the cam surfaces thereof may be so relatively positioned as cooperatively to provide a notch indicated at 76 in the cam surface which may be varied in length up to substantially the length of the cam surface 752. A lever arm 77 having a depending lip 79 of sufficient width to engage both of the cam elements of cam 75 is pivotally supported at one end as indicated at 791 with the lip thereof in engagement with the surface of cam 75. Hence, when cam 75 is rotated, arm 77 will be lowered when it leaves the surface 751 and enters the notch 76 and will again be raised when it engages the intermediate surface 753 and passes to the surface 751. By varying the extent of the notch 76, therefore, the time interval during which arm 77 is lowered may be varied with respect to the time interval during which the cam makes one com-

plete revolution. Furthermore, if both cam elements are adjustable relative to shaft 54, the interval during which arm 77 is lowered may be varied with respect to the interval during which the cam is actuated. A switch 78 is mounted upon arm 77 and is connected by means of conductors 811 and 812 in circuit with the stoker motor 88 which operates the fuel supplying and ash removing devices. When arm 77 is lowered and the lip 79 thereof lies within the notch 76, the switch 78 is closed and, of course, when the lip engages the surfaces 751 of the cam elements, the switch is open.

In connection with the cams 62 and 75, above described, it should be noted that, due to the provision of switch 208 which maintains the operation of the pilot motor 45 after it has once started, each cycle of operation of said motor comprises one complete revolution of the shaft 54. Hence, generally speaking, cams 62 and 75 may be so constructed and arranged upon the shaft 54 that an operation of the devices controlled thereby may be effected simultaneously or in substantially any desired sequence and the time interval during which the cams operate the various devices may be adjusted relative to the interval during which the pilot motor 45 is operated or, in other words, they may be fixed to operate their associated devices during any desired part of the cycle of operation of said pilot motor.

We prefer so to arrange our control system that an operation of the draft fan motor cannot occur until after a short interval has elapsed following the termination of an operation of the stoker mechanism. This time interval is preferably sufficient to permit at least the larger ash particles to settle upon the fuel bed, after a shaking operation of the grate, before draft is supplied to the furnace.

The ability to vary the period of operation of the stoker motor 88, thereby varying both the quantity of fuel delivered to the magazine in each cycle of operation, and the quantity of ashes set free in the fuel bed by the burning of a like quantity of fuel during the elapsed period from the preceding stoking operation, makes it possible to avoid such an accumulation of ashes in the fuel bed as would appreciably affect combustion conditions therein. Lengthening the period, of course, increases the charge in each cycle and shortening the period decreases the charge. In practice it is found that about 6 oz. of free ash may be permitted to accumulate in a fuel bed having a grate with an area of 1 sq. ft. Hence, to maintain uniform combustion conditions when using high ash fuel the quantity of fuel delivered in each charge is preferably less than would be the case if a low ash fuel were being supplied. In addition to having means for adjusting the proportion of time of stoking to the time required for the complete cycle, we may also provide an adjustable fuel supplying device (not illustrated) by which the quantity of fuel delivered to the fuel conveyor per linear foot of movement thereof may be varied.

The operation of the device embodying our invention is as follows: Assuming that the crank arm 31 actuated by draft control motor 11 is in the draft off position and that the bi-metallic arm 28 of thermostat 10, due to a drop in temperature, engages the contact 29a, a circuit will be completed to motor 11 provided switch 200 and contacts 61R of switch 61 are in their closed positions to complete the circuit through con-

ductors 202 and 203. The switch 200 is actuated by crank arm 53 secured to shaft 54 actuated by motor 45 and is so arranged that the circuit therethrough is broken when the stoker motor 88 is in operation. Switch 61 is mounted on the lever 58 which is tilted by the fuel-follower rod 46 and, in the position illustrated in Fig. 4, the contacts 61R at the lower end of the mercury switch 61 complete a circuit through switch 200 and the thermostat 10 to the motor 11. This circuit through contacts 61R of switch 61 is normally closed but when the fuel in the magazine has subsided sufficiently to allow the follower rod to reverse the inclination of the lever 58, the foregoing circuit is broken at the contacts 61R of switch 61 and an operation of draft control motor 11 to draft on position is prevented.

However, ordinarily when arm 28 of the thermostat engages the contact 29a the circuit to motor 11 is completed as follows: from the leg 25 of the main line conductors through conductors 201 and 202, through contacts 61R of switch 61, conductor 219 and switch 200, conductor 203 to contact 29a and thence through arm 28, conductor 27, jumper connection 26 and spring arm 16, engaging contact 22, and through conductor 24 to one side of the motor 11, the other side of the motor being connected through conductor 204 to the other leg 25a of the main line conductors. When motor 11 commences to rotate, the cam 13 on the crank shaft 32, operated by said motor, rotates and forces the boss 19 on the arm 15 from the notch 14 thereby forcing said arm into engagement with the contact 21. Hence, a circuit shunting the thermostat 10 and contacts 61R of switch 61 and switch 200 is created from the conductor 201 through contact 21, arm 15, jumper connection 26, arm 16 and contact 22 to one side of the motor and, therefore, continuous operation of the motor is insured until the crank arm 31 and shaft 32 have revolved through 180° at which position thereof the cam-engaging boss 20 on arm 16 drops into the recess 14 of cam 13 and thereby breaks the circuit between arm 16 and contact 22.

When sufficient heat has been developed by the furnace, the bi-metallic arm 28 of thermostat 10 engages contact 29 to effect an operation of motor 11 to its idling position. Since in the last described position of cam 13, in which position thereof the motor 11 and crank arms 31 and 38 are in the draft-on position, a circuit from leg 25 of the main lines had been created through conductors 201 and 23, contact 21, arm 15, jumper 26 and conductor 27 to the bi-metallic arm 28, engagement of arm 28 with contact 29 will complete a new circuit to the motor including the foregoing described partial circuit and conductor 30 which connects contact 29 with one side of the motor. After the crank arms and shaft 32 have revolved through a second arc of 180°, the boss 19 again drops into the notch 14 thereby breaking the circuit between contact 21 and arm 15 and reconnecting the motor 11 in the circuit including contact 29a; in other words, the circuit is again closed for operating the motor 11 when the arm of the thermostat engages contact 29a.

The above described circuits embody devices which control the normal operation of the furnace through a cycle wherein the furnace is operated under forced draft and under idling conditions and this cycle of operation is carried out under heat and no-heat demands, respectively, to which the thermostat 10 is responsive. The op-

eration of these circuits to effect an operation of the furnace under forced draft is prevented while a stoking operation is being carried out because of the switches 61 and 200. A stoking operation should not occur, however, when the motor 11 has placed the crank arms 31 and 38 in draft-on position. Hence, switch 61 is so arranged that when arm 58 is tilted by the follower rod 46, the circuit, above described to contact 29a of the thermostat, is broken and a circuit including the contacts 61L of switch 61 and the conductors 205 and 206 is closed which serves as a direct connection between the bi-metallic arm 28 and contact 29 and, therefore, when this circuit is closed through the actuation of switch 61, the motor 11 is actuated to move the crank arms 31 and 38 to idling position. With the foregoing arrangement, draft will be cut off and a stoking operation may occur.

While we have described a draft control motor 11 which is driven in the same direction and associated means which permit combustion under draft to take place after the shaft, actuated by said motor, has made one half revolution, and which stop such combustion and permit a stoking operation to take place after the shaft, operated by said motor, has made another half revolution, it will, of course, be understood that the same result may be accomplished by a reversible or other two positional motor, and that the motor and associated parts are intended to illustrate one embodiment of our invention.

Since switch 60 will be closed when the last described circuit is made through contacts 61L of switch 61 which, of course, has no utility in the event motor 11 is, at this time, in the idling position, the circuit to the motor 45 which controls the stoking cycle is closed through switch 60. In series with switch 60 is a second switch 43 which is closed only when arm 40 upon which it is mounted, has an inclination the reverse of that shown. Hence, switch 43 will be closed when the motor 11 is in idling position and, therefore, motor 45 cannot effect a stoking operation unless the draft is cut off to the furnace. Assuming that switch 43 is closed and that the fuel-follower rod 46 effects a closure of switch 60, the circuit to motor 45 will be completed and a continued operation of motor 45 to effect a rotation of the shaft 54, actuated thereby, through 360° is insured by the provision of the automatic switch indicated generally at 208 which shunts the switches 43 and 60 following an initial energization of motor 45 through a closure of these switches. A rotation of shaft 54 through 360°, of course, serves through the medium of associated devices, hereinbefore described, to close and open the idling air inlet port 74, to open and close the fuel gate 68 in the chute to the fuel magazine, to raise and release the follower rod 46, to close and open the switch 78 which controls the stoker motor 88 and open and close switch 200. By raising and releasing the rod 46, the depth of fuel in the magazine may be gauged and if an insufficient amount of fuel has been supplied to the magazine, the rod will again close switch 60 and effect another operation of motor 45 through a stoking cycle.

It will be observed that with the foregoing arrangement of circuits, draft will be cut off to the furnace under all circumstances when the fuel-follower rod moves to a position indicating that a stoking operation should occur to supply fresh fuel to the furnace and that before the stoking operation occurs an actuation of the

motor 11 to draft-off position, will take place. When, however, a stoking operation commences, the draft cannot be turned on and automatic control of the furnace by the thermostat is temporarily suspended during the stoking operation. In this connection it will be noted that when the motor 45 is energized to effect a stoking operation, switch 200 is opened and, therefore, the circuit to motor 11 is opened and an actuation thereof cannot occur to open the drafts and close the circuit to the draft fan motor 44.

It will also be noted that in the cycle of operation of motor 11, shaft 32 is rotated first through 180° and then through another 180°. When the shaft rotates through the first 180°, for example, it serves to open air inlet valve 34, close switch 42 and open switch 43 thereby supplying draft to the furnace and preventing an operation of the pilot motor 45. When the shaft rotates through the second 180°, it functions through associated means to close the main inlet valve 34, to open switch 42, cutting out the fan motor 44 and closing switch 43 in the circuit to pilot motor 45.

It will be understood that the term "fuel bed" as employed in the appended claims is used in its usual sense and, as applied to the embodiment of our invention herein illustrated, is intended to designate the bed of fuel which is above the grate and within the fuel magazine.

While we have described our invention in its preferred embodiment, it is to be understood that the words which we have used are words of description rather than of limitation and that changes within the purview of the appended claims may be made without departing from the true scope and spirit of our invention in its broader aspects.

What we claim is:

1. In a control system for a furnace comprising a grate adapted to support a bed of fuel, electrically operated means for producing a draft through said bed of fuel, means for supplying fuel to the bed of fuel, means for controlling the draft-producing means, means for preventing an operation of said fuel-supplying means while said draft-producing means is in operation, means for preventing an operation of said draft-producing means while said fuel-supplying means is in operation, and means operable in response to subsidence of the fuel in said furnace for operating said two last mentioned means.

2. In a control system for a furnace comprising a grate adapted to support a fuel bed, an electrically operated means for producing a draft through said fuel bed, means for supplying fuel to said fuel bed, a thermostat for controlling the operation of said draft-producing means, a switch for controlling the operation of said fuel-supplying means and a switch in the circuit of said electrically operated draft-producing means, and means including a common means operable in response to the subsidence of fuel in the fuel bed of said furnace for effecting an operation of both of said switches.

3. In a control system for a furnace comprising a grate adapted to support a fuel bed, an electrically operated means for producing a draft through said fuel bed, means for removing ashes from said fuel bed, a thermostat for controlling the operation of said draft-producing means, a switch for controlling the operation of said ash-removing means and a switch in the circuit of said electrically operated draft-producing means, and means including a common means operable in response to the subsidence of fuel in the fuel

bed of said furnace for effecting an operation of both of said switches whereby to open a first thereof and to close the second and to open the second and close the first.

5 4. In a control system for a furnace comprising a grate adapted to support a fuel bed, means for producing a draft through said fuel bed, means for removing ashes from said fuel bed, means for controlling the operation of said draft-producing means, means for controlling both the operation of said draft-producing means and the operation of said ash-removing means, said control means being operable in response to subsidence of fuel in the fuel bed of said furnace to terminate an operation of said draft-producing means if in operation and to effect an operation of said ash-removing means, and means for delaying an operation of said draft-producing means for a time interval after the operation of said ash-removing means has terminated.

15 5. In a control system for a furnace comprising a grate adapted to support a bed of fuel, electrically operated means for producing a draft through said fuel bed, a main air inlet port in said furnace and a valve therein adapted to admit sufficient air for combustion at a maximum rate of combustion, means for controlling the operation of said draft-producing means, control means for opening and closing said main air inlet valve; said control means being so correlated and arranged that said main air inlet valve will be open when said draft-producing means is in operation and will be closed when said draft-producing means is inoperative, an idling air inlet port in said furnace and a valve therein adapted to admit air to support combustion of fuel in the fuel bed, means for removing ashes from said fuel bed, means for controlling the operation of said ash-removing means, and control means for opening and closing said idling air inlet valve; said last mentioned control means and said means for controlling the operation of the ash-removing means being so constructed and arranged that said idling air inlet valve will be closed during and for a brief time interval after an operation of said ash-removing means.

20 6. In a control system for a furnace comprising a grate adapted to support a bed of fuel, electrically operated means for controlling the draft through said bed of fuel, means for removing ashes from said bed of fuel, a thermostat, a switch connected in circuit with said draft-controlling means, a first electrical means electrically connected with and controlled by said thermostat and operatively associated with said switch for opening and closing said switch, an electrical circuit including a second electrical means for controlling the operation of said ash-removing means, and a switch in said circuit operatively associated with said first electrical means whereby to be opened and closed thereby; said switches being so constructed, correlated and arranged that an operation of said first electrical means will open one thereof and close the other.

25 7. In a control system for a furnace comprising a grate adapted to support a bed of fuel, electrically operated means for controlling the draft through said bed of fuel, means for removing ashes from said bed of fuel, a thermostat, a first switch connected in circuit with said draft-controlling means, a first electrical means electrically connected with and controlled by said thermostat and operatively associated with said switch for opening and closing said switch, an electrical circuit including a second electrical

means for maintaining an operation of said ash-removing means for a time interval, a second switch in said circuit operatively associated with said first electrical means whereby to be opened and closed thereby; said first and second switches being so constructed, correlated and arranged that an operation of said first electrical means will open one switch and close the other, and means operable in response to subsidence of fuel in said furnace for closing the electrical circuit to said second switch and for effecting an operation of said draft controlling means to prevent the passage of a draft through said bed of fuel.

8. In a control system for a furnace comprising a grate adapted to support a bed of fuel, electrically operated means for producing a draft through said bed of fuel, electrically operated means for regulating the quantity of material on said fuel bed, thermostatically controlled means for controlling the operation of said draft-producing means, means for controlling the operation of said material-regulating means, a pair of switches connected in circuit with said last mentioned means, one of said switches being associated with and operable by said thermostatically controlled means to effect a closure of said switch when an operation of said draft-producing means is stopped, and means operable in response to subsidence of fuel in the fuel bed of said furnace for closing the other of said pair of switches and for effecting an operation of said thermostatically controlled means to terminate an operation of said draft-producing means if said draft-producing means is in operation.

9. In a control system for a furnace comprising a grate adapted to support a fuel bed, means forming a passage above and below said fuel bed for the flow therethrough of air to said fuel bed and the flow of products of combustion therefrom, movable means associated with said passage-forming means and operable to pass air and substantially to prevent the free passage of air to said fuel bed, a first control means for said second mentioned means, means for supplying fuel to said bed of fuel, and a second control means operable in response to subsidence of fuel in the fuel bed of said furnace for controlling an operation of both said second mentioned means and said fuel-supplying means; said first and second control means being so constructed, correlated and arranged as to prevent the supply of air to said fuel bed when said fuel-supplying means is in operation.

10. In a control system for a furnace comprising a grate adapted to support a fuel bed, means for removing ashes from said fuel bed, means forming a passage above and below said fuel bed for the flow therethrough of air to said fuel bed and the flow of products of combustion therefrom, movable means associated with said passage-forming means and operable to pass air and substantially to prevent the free passage of air to said fuel bed, a first control means for said third mentioned means, and a second control means operable in response to subsidence of fuel in the fuel bed of said furnace for controlling an operation of both said third mentioned means and said ash-removing means; said first and second control means being so constructed, correlated and arranged as to prevent the supply of air to said fuel bed when said ash-removing means is in operation.

11. In a control system for a furnace of the character described comprising a grate adapted to support a fuel bed, means for producing a

draft through said fuel bed, means for supplying fuel to the bed of fuel, a first means for controlling the operation of said draft-producing means, and a second means operable in response

5 to subsidence of fuel in the fuel bed of said furnace for controlling both the operation of said fuel-supplying and said draft-producing means; said first and second control means being so constructed, correlated and arranged as to prevent the operation of said draft-producing means when said fuel-supplying means is in operation.

12. In a control system for a furnace of the character described comprising a grate adapted to support a fuel bed, means for removing ashes 15 from said fuel bed, means for producing a draft through said fuel bed, a first means for controlling the operation of said draft-producing means, and a second means operable in response to the subsidence of fuel in said fuel bed for 20 controlling both the operation of said ash-removing and said draft-producing means; said first and second control means being so constructed, correlated and arranged as to prevent the operation of said draft-producing means when said ash-removing means is in operation.

13. In a control system for a furnace of the character described comprising a grate adapted to support a bed of fuel, means for supplying fuel to the bed of fuel, a first electrical operating means therefor, means for producing a draft through said bed of fuel, a second electrical operating means therefor, a thermostat for controlling said second electrical operating means, electrical circuits including said electrical operating means and electrical means for controlling the circuits thereto; said last mentioned means being operable to open the circuit to said second electrical operating means when closing a circuit to said first electrical operating means.

14. In a control system for a furnace comprising a grate adapted to support a fuel bed, means forming a passage above and below said fuel bed for the flow therethrough of air to said fuel bed and the flow of products of combustion therefrom, movable means associated with said passage-forming means and operable to pass air and substantially to prevent the free passage of air to said fuel bed, control means for controlling the operation of said second mentioned means, means for supplying fuel to said bed of fuel, control means for controlling the operation of said fuel-supplying means and means for preventing an operation of said second mentioned means to pass air to said fuel bed while and each time said fuel-supplying means is in operation.

15. In a control system for a furnace comprising a grate adapted to support a fuel bed, means forming a passage above and below said fuel bed for the flow therethrough of air to said fuel bed and the flow of products of combustion therefrom, movable means associated with said passage-forming means and operable to pass air and substantially to prevent the free passage 65 of air to said fuel bed, control means for controlling the operation of said second mentioned means, means for removing ashes from said bed of fuel, control means for controlling the operation of said ash-removing means and means for preventing an operation of said second mentioned means to pass air to said fuel bed while and each time said ash-removing means is in operation.

16. In a control system for a furnace comprising a grate adapted to support a fuel bed, means

for producing a draft through said bed of fuel, means for controlling said draft-producing means, means for removing ashes from said fuel bed, means for controlling the operation of said ash-removing means and means for preventing an operation of said draft-producing means while and each time said ash-removing means is in operation.

17. In a control system for a furnace comprising a grate adapted to support a fuel bed, means for producing a draft through said bed of fuel, means for controlling said draft-producing means, means for removing ashes from said fuel bed, means for controlling the operation of said ash-removing means and means for preventing an operation of said draft-producing means when said ash-removing means is in operation and for a time interval after an operation of said ash-removing means has terminated.

18. In a control system for a furnace comprising a grate adapted to support a fuel bed, an electrically operated fuel-supplying means including a tubular chute arranged to pass fuel to the fuel bed, means for controlling the admission of air to said furnace for combustion purposes, a valve arranged in said chute substantially to prevent, when closed, the flow of gas through said chute, electrical means for controlling the operation of said fuel-supplying means and for effecting an opening and closing of said valve in said chute, and means for actuating said air-control means substantially to prevent the admission of air to the furnace for combustion purposes when said valve in said chute lies in other than substantially closed position.

WARREN S. BLAUVELT.
